UNITED STATES PATENT OFFICE.

DOROTHY HELEN ISAACS AND LOWA BELLE SMITH, OF SPIRIT LAKE, IDAHO.

DESIGN FOR A DOLL.

59,847.

Specification for Design.

Patented Nov. 29, 1921.

Application filed April 20, 1921. Serial No. 463,055. Term of patent 7 years.

To all whom it may concern:

Be it known that we, DOROTHY HELEN ISAACS and LOWA BELLE SMITH, citizens of the United States, residing at Spirit Lake, in the county of Kootenai and State of Idaho, have invented a certain new, original, and ornamental Design for Dolls, of which the following is a specification.

Said design consists in a unique style and design for a doll of the general character and appearance shown in the accompanying drawing, which is a front view of a doll embodying our said design.

What we claim is:

The ornamental design for a doll as herein shown and described.

In witness whereof, we have hereunto set our hands and seals at Spirit Lake, Idaho, this 15th day of April, A. D. nineteen hundred and twenty-one.
